United States Patent Office.

ANDREW HARTUPEE, OF PITTSBURG, PENNSYLVANIA.

Letters Patent No. 77,038, dated April 21, 1868.

IMPROVEMENT IN GRATE-BARS.

The Schedule referred to in these Letters Patent and making part of the same.

TO ALL WHOM IT MAY CONCERN:

Be it known that I, ANDREW HARTUPEE, of the city of Pittsburg, in the county of Allegheny, and State of Pennsylvania, have invented a new and useful Improvement in Grate and Bearing-Bars for Furnaces; and I do hereby declare the following to be a full, clear, and exact description thereof, reference being had to the accompanying drawing making a part of this specification, in which—

Figure 1 is a front elevation of a furnace fitted with my improved grate and bearing-bars.

Figure 2 shows the grate-bar in side view, and the bearing-bars in cross-section, and

Figure 3 is a top view of my improved grate-bar, which shows the apertures through which air is admitted to the fire of the furnace.

Like letters indicate like parts in each.

My improvement is particularly designed for use in puddling, iron, or rolling-mill furnaces, though it is advantageously applicable to other furnaces in which a considerable amount of fuel is employed, and a high degree of heat required; and the nature of it consists, first, in making an improved grate-bar of T-shaped iron, either rolled or cast, with or without the usual apertures in its upper or broad face for the admission of air; second, in an arrangement of circular apertures through the grate-bar near to each edge; third, in an arrangement of cross-bearing bars, so notched as to receive the lower or flanged part of the T-iron bar, for the purpose of holding it steadily in place, and enabling it more easily to be removed and replaced in cleaning the furnace.

To enable others skilled in the art to make and use my invention, I will proceed to describe its construction and manner of use.

a represent the side walls of a heating-furnace, into which are built the cross-bearing bars *b*. These are properly notched at suitable distances, as at *c*, so as to receive the lower or flanged parts *d* of the T-shaped bars. The distances between the notches *c* should be such that the proper apertures *e* will be left between the bars. These bars I make of either rolled or cast T-iron, the upper or broad part forming the upper part, *d*, of the bar, and the lower or flanged part *d'*, forming a brace or rib to support and add strength to the bar, as well as acting as a guide in the notches *c* to keep it in place.

In either side of the rib *d'*, at its junction with the broad face *d* of the bar, I make a series of similar apertures, *i*, as shown in fig. 4, near to the outer edges of the upper face of the bar. Such apertures I make of any size that may be desired, but with particular reference to securing the required amount of air without unnecessary loss of fuel in consequence of its falling through.

In puddling and iron-mill furnaces, the grate-bars usually employed consist of bar-iron, cut to the desired length, which are laid on flat cross-bearers. As such bars have nothing to hold them at the required distances from each other, they are liable to become displaced, so as to leave large apertures, through which fuel falls and is lost; and, as they are about three inches in width, they interfere seriously with a free supply of fresh air to the fire.

These difficulties I wholly avoid by the use of a T-iron grate-bar, with apertures as described, and set in notches *e*, which are cut in the cross-bearers *b*. I also secure a far stronger and more durable bar by means of the rib *d'*, with but slight increase of cost. They can be kept free of cinder, clinker, and ashes as easily as the ordinary grate-bar, through the apertures *e*, or, when required, can be drawn from the furnace by the handles *f*, and replaced or renewed.

What I claim as my invention, and desire to secure by Letters Patent, is—

1. The notched cross-bearers *b* of a furnace, in combination with the rib *d'* of a T-shaped grate-bar, of either cast or wrought-iron, constructed and used substantially as and for the purpose above set forth.
2. A T-shaped grate-bar, having a series of circular apertures near to each end, substantially as herein-before described.
3. A T-iron grate-bar, constructed with or without apertures through it, substantially as above described, as a new article of manufacture.

In testimony whereof, I, the said ANDREW HARTUPEE, have hereunto set my hand.

Witnesses:

A. S. NICHOLSON,
G. H. CHRISTY.

ANDREW HARTUPEE.
